UNITED STATES PATENT OFFICE.

BENJAMIN C. SMITH, OF BAYONNE, NEW JERSEY, ASSIGNOR TO STANDARD MOTOR CONSTRUCTION COMPANY, OF JERSEY CITY, NEW JERSEY, A CORPORATION OF NEW JERSEY.

OIL-BURNING ENGINE.

Application filed December 4, 1924. Serial No. 753,850.

This invention relates to fuel burning engines of the so called Diesel type, and particularly to such engines as employ a number of cylinders.

5 The main object of the invention is to provide simple and effective means whereby any one of the cylinders may be caused to "idle", whereby the operator in charge may make certain repairs without stopping the entire 10 motor. For example, the fuel injection valve sometimes requires cleaning, and to do this requires its removal. This is one of the things that may be easily and safely accomplished by the use of my invention.

15 In the drawings—

Fig. 1 is a vertical cross sectional view showing such parts as are necessary to an understanding of my invention;

Fig. 2 is a relatively enlarged side elevation of certain parts;

Fig. 3 is a cross sectional view, certain parts being shown in detail and in elevation;

Fig. 4 is a side view of a detail;

Fig. 5 is a sectional view of the head of 25 one cylinder, taken in a plane at right angles to the plane of the section in Fig. 1;

Fig. 6 is a plan view of the head of one of the engine cylinders and certain associated parts.

30 I have not attempted herein to show a complete engine or the several cylinders thereof, since each of the cylinder units will correspond substantially and therefore a description of one will suffice for all.

35 1 is an engine base. 2 is the crank shaft. 3 is a cylinder. 4 is the working piston. 5 is a connecting rod. 6 is a fuel feed valve through which fuel is forced. This valve is mounted in the cylinder head and may be of 40 any suitable construction. 7 is what I will term an overhead rocker, pivoted at 7^a for operating the valve 6. 7^b is a fork on rocker 7 which fork engages a part of the fuel feed valve to lift and open it. 8 is a draw-rod 45 connected to the rocker 7. 9 is a slotted pivot stud at the lower end of the draw-rod 8. 10 is what I will term a lower rocker pivoted on a suitable supporting member that I will term a short shaft 11, there being 50 one such support for each cylinder unit.

10^a is a nose on the lower rocker, engaging in the slot of the pivot stud 9. 12 is a cam shaft for all of the cylinders the same being driven from the crank shaft in the usual 55 manner. 13 is a cam for the rocker 10, which

operates the fuel feed valve 6. Each short shaft 11 has a control lever 14 whereby its angular position may be manually varied. 15 is an air inlet valve for the cylinder 3. 16 is an upper rocker therefor. 16^a is a 60 pivot for the rocker 16. 16^b is a nose on the rocker which nose engages the inlet valve stem. 17 is a push rod for the upper rocker 16. 18 is what I will term a lower rocker for engaging the lower end of the push rod 65 17 to lift the same and open valve 15. 19 is an eccentric portion on the supporting shaft 11, upon which eccentric portion the rocker 10 for the fuel feed valve is mounted. 20 is a cam on the cam shaft 12 for operating 70 the air inlet valve rocker 18. 21 is a dog secured to the shaft 11 and co-operating with the rocker arm 18 in the manner and for the purpose hereinafter described. 22 is an exhaust valve. This exhaust valve may be operated from the cam shaft 12 by a similar 75 means and in the same manner as the inlet valve 15 the cams being so timed as to operate said valves in the proper order and at the proper time. 23 represents a push rod for 80 the exhaust valve, and 24 represents what I will term the lower rocker therefor. 25 represents the cam for operating the lifter 24 and thereby the exhaust valve 22.

The cam for controlling the operation of 85 the fuel feed valve 6 is also positioned properly, so that fuel will be injected into the cylinder at the proper time and for the proper period.

It may be assumed that, when the engine is 90 operating normally, the shaft 11 will occupy the position shown in Fig. 3. If, for any reason, it should be desirable to remove the fuel feed valve 6, it is manifest that this could not be done with ease or safety unless 95 the suction and compression within the cylinder 3 is relieved and unless the means for operating the fuel feed valve is rendered ineffective for the time. To that end the operator has but to grasp the lever 14 and swing 100 it back, which will first cause the eccentric portion 19 to lift the outer end of the rocker 10 until it is out of the range of operation of the cam 13. The dog 21 is so positioned on the short shaft 11 that a further turning 105 of shaft 11 will cause said dog to engage one of the other rockers, for example the rocker 18, to lift it to a sufficient extent to open its complementary valve and hold the same open (until the shaft 11 is swung back) thus 110

freely venting the interior of the cylinder 3 and making it possible to easily and safely remove the fuel valve 6, or to make any other repair on that particular cylinder as might 5 be effected under such conditions, that cylinder being, during the period of repair, rendered "dead" although the balance of the cylinders are working.

It is obvious that it is immaterial whether 10 it is the exhaust valve or the air inlet valve that is held open during the period when it is desired to "vent" the cylinder.

In the drawings the lever 14^a represents 15 the control lever for the so called short shaft of the next adjacent cylinder unit.

I have shown my invention in preferred 20 form only being aware that many changes in the design and construction of the various parts may be made without departing from the scope thereof.

I claim:

1. In a four-cycle engine of the character described, a cylinder, an air intake valve, an exhaust valve, a fuel feed valve, a cam shaft, 25 separate rockers actuated thereby for operating said valves, a shaft support for said rockers, means carried by said shaft support for actuating the rocker for the fuel valve, and other means carried by said shaft for actuating the rocker for one of the other

valves, said means being so positioned on 30 said shaft relatively to each other that a rotation of the shaft to one position will first render the fuel valve rocker ineffective, and a further rotation to another position will operate the rocker for another one of the 35 valves to open the same while still continuing to render the fuel valve rocker ineffective.

2. In a four-cycle engine of the character described, a cylinder, an air intake valve, an exhaust valve, a fuel feed valve, a cam shaft, 40 separate rockers actuated thereby for operating said valves, a shaft support for said rockers, an eccentric carried by said shaft support for actuating the rocker for the fuel 45 valve, and a dog carried by said shaft for actuating the rocker for one of the other valves, said eccentric and dog being so positioned on said shaft relatively to each other that a rotation of the shaft to one position 50 will first render the fuel valve rocker ineffective, and a further rotation to another position will operate the rocker for another one of the valves to open the same while 55 still continuing to render the fuel valve rocker ineffective.

BENJAMIN C. SMITH.
